NOVEL STEROIDAL 17-KETALS AND
RELATED COMPOUNDS

Herchel Smith, Wayne, Leland L. Smith, Malvern, and James F. Fisher, Villanova, Pa., assignors to American Home Products Corporation, New York, N.Y., a corporation of Delaware
No Drawing. Filed Aug. 24, 1962, Ser. No. 219,115
5 Claims. (Cl. 260—239.55)

The present invention relates in general to certain new and novel 17-ketals of estrogenic steroids, particularly to those which are partially dehydrogenated. More particularly, it concerns the preparation of novel 17-ketals of 6-dehydroestrone, 7-dehydroestrone and 14-dehydroestrone and the 3-ethers and esters thereof, as well as pharmaceutical compositions containing many of these compounds.

The compounds of the invention may generally be depicted by the structure:

wherein R represents a substituent selected from the group consisting of hydrogen, lower alkyl, lower alkenyl, cycloalkyl, lower aralkyl and acyl; S, T and U represent a member selected from the group consisting of double unsaturated and single saturated carbon-carbon bonds, and W represents a member selected from the group consisting of alkylendioxymethylene, alkylenedithiomethylene and alkylenthioxymethylene, with the proviso (1) that one of S, T and U must be a double bond and the other two must be saturated single bonds; and (2) that when R is hydrogen or acyl, U must be a saturated single bond.

In the above definition of the general class of compounds of the invention, the term lower alkyl is intended to refer to those alkyl groups having from 1 to about 20 carbon atoms and more particularly to those having less than 10 carbon atoms. The alkyl group may be normal or branched in structure, although the normal chain is generally preferred. Some examples of these would be methyl, ethyl, propyl, isopropyl, butyl, isobutyl, pentyl, octyl, dodecyl, and cetyl, to name a few. The term lower cycloalkyl refers to that substituent wherein the carbon atoms are joined in a carbocyclic ring which is generally 5 or 6 membered, but which may contain a smaller or larger number of carbon atoms subject to the practical limit of stability of such structures. The term lower aralkyl as employed herein refers in general to an alkyl substituted aromatic ring structure which may contain up to about 20 carbon atoms in the substituted alkyl chain attached thereto. An example of this type of substituent would be for instance benzyl, phenylethyl, phenylisopropyl and the like. The term acyl as employed herein refers to a substituent derived from a mono-, di-, or polycarboxylic organic acid which may be saturated or unsaturated. These radicals are, of course, obtained from any suitable organic acid by removal of a hydroxyl group therefrom. Such acyl radicals as the alkanoyl radicals acetyl and propionyl derived from acetic and propionic acids respectively and the aryloyl radical benzoyl derived from benzoic acid would therefore serve as examples of this type of substituent.

2

The ketal substituent present as W in the 17-position of this novel class of compounds is considered to be an essential element of such structures. It is intended by the definition of alkylendioxymethylene, alkylenedithiomethylene and alkylenthioxymethylene as employed herein to embrace any and all forms of such ketals which can contain up to about 10 carbon atoms but preferably about 2 to 6 carbon atoms therein. These ketals can be of the closed or open chain type, both of which would behave in a similar manner. The term alkylenthioxymethylene involves those ketal substituents wherein both oxygen atoms have been replaced by a sulfur atom.

Some specific compounds which fall within the broad scope of the invention may be noted. To cite a few as examples one may mention compounds such as the 7- or 14-dehydroestrone 17-ethylene ketal, 6-dehydroestrone 17-ethylene ketal-3-methyl ether, 14-dehydroestrone 17-ethylene ketal-3-methyl ether, 7-dehydroestrone 17-ethylene ketal-3-methyl ether, 14-dehydroestrone 17-ethylene ketal-3-cyclopentyl ether, 7-dehydroestrone 17-ethylene ketal-3-cyclopentyl ether, 6-dehydroestrone 17-ethylene ketal-3-cyclopentyl ether, 14-dehydroestrone 17-trimethylene ketal-3-methyl ether, 14-dehydroestrone 17-ethylene ketal-3-acetate, 14-dehydroestrone 17-ethylene ketal-3-benzoate, 7-dehydroestrone 17-ethylene ketal-3-benzoate, 6-dehydroestrone 17-ethylene thioketal 3-methyl ether, 7-dehydroestrone 17-ethylene thioketal 3-methyl ether, 14-dehydroestrone 17-ethylene dithioketal, estrone 17-ethylene dithioketal 3-methyl ether, to name a few of our novel compounds.

The novel compounds of the invention may be prepared by way of several general methods of preparation. One of these may be outlined as follows:

In the above reaction scheme the symbol X represents a halogen atom, while R represents one of the substituents previously defined. The reaction involves treatment of the known compound estrone methyl ether (I) with a suitable acylating agent such as an alkenyl acylate such as isopropenyl acetate at temperatures up to the reflux temperature of the acylating agent for from about 2 to 24 hours' duration to form the corresponding 17-enol acetate (II). The enol acetate is halogenated with a reagent suitable for introducing a halogen atom at the 16-position, i.e., bromine may be employed in the presence of any suitable inert solvent such as carbon tetrachloride to obtain the 16-halogeno substituted estrone methyl ether (III). The treatment of (III) with a suitable ketalizing agent such as ethylene glycol and p-toluenesulfonic acid in an inert solvent such as benzene or the like at temperatures up to the reflux temperature of the solvent for from 2 to 24 hours will form the 16-halogenated 17-ketal analog (IV). At this point, dehydrohalogenation of (IV) by treatment with a suitable dehydrohalogenation agent such as potassium tertiary butoxide or the like at temperatures up to the reflux point of the solvent removes the halogen substituent and forms the Δ^{15} -estrone ketal (V). Treatment of this compound with p-toluenesulfonic acid causes the Δ^{15} -bond to shift to the Δ^{14} -position and removes the ketal group to give the Δ^{14} -estrone methyl ether (VI). This compound when ketalized in the same manner as above indicated for the ketalization of (III) above yields a compound (VII) of the final class of compounds disclosed and claimed as this invention wherein T is a double bond.

The compounds of the invention wherein S is a double bond may be prepared in the following manner if desired:

In the above reaction the known compound equilin (VIII) is reacted with a molar equivalent quantity of a suitable ketalizing agent such as ethylene glycol and p-toluenesulfonic acid in an inert solvent such as benzene under the time and temperature conditions expressed above for ketalization to give the corresponding 17-ketal (IX) which is then etherified with a suitable alkylating agent to transform the hydroxy group in the 3-position to a corre-

sponding alkoxy substituent yielding the final product (X).

In still another variant of the methods of preparation of the compounds of the invention, the 17-ketals of 6-dehydroestrone and esters and ethers thereof may be obtained by following the reaction scheme hereinbelow:

In the above reaction the known compound 6-dehydroestrone (XI) is ketalized in the manner above described to yield the corresponding 17-ethylene ketal (XII) which is etherified or esterified to the corresponding 3-substituted ether or ester (XIII) by methods well known to the prior art to obtain still another variant of these novel compounds having a Δ^6 double bond.

In this method of preparation in the above reaction schemes where it is desired to prepare the 17-substituted hemithioketal instead of the alkylenedioxy type a reagent such as thioethanol is substituted for alkylene glycol in the ketalizing step of the synthesis. In the same manner where the dithio ketal is desired, a reagent such as ethanedithiol is substituted for the alkylene glycol employed in the ketalizing steps.

The compounds of the invention are useful in the field of experimental pharmacology as well as being valuable as intermediates for further steroid synthesis in preparing new steroid compounds. In addition, many of the compounds of the invention have been found to demonstrate high antilipemic properties coupled with low feminizing action. Also, besides having capacity to regulate blood lipids, the compounds are useful for their general hormonal effect, particularly in the female. Therefore many of the compounds would be expected to exhibit utility in those areas where estrogens are employed, such as female hypogonadism, amenorrhea, dysmenorrhea metrorrhagia, ovulation block and contraception, pregnancy maintenance, arteriosclerosis, osteoporosis, menopausal symptoms, infertility, regulation of water balance, functional uterine bleeding, and the like.

The novel compounds of the invention when contemplated for use in pharmaceutical products may be employed in combination if desired with a large number of compatible diluents, carriers, and the like to form a pharmaceutical composition. Such liquid carriers as mineral oil or a lower aliphatic alcohol may be used where injectables are to be prepared. Glycerine or the like may be used where a syrup is to be used to administer the compound. Solid excipients, binders, extenders or carriers such as carboxymethylcellulose, starches, sugars and the like may be employed where tablets or powders are to be employed as a means of administration. The dosage of the compounds will vary with the severity of the ailment and in general can vary from 0.5 to 100 mg./kilo of body weight per day depending upon the many factors of the case involved.

The invention is further illustrated by the several following examples of preparation of selected members of the series. It is, of course, understood that these examples

are purely by way of illustration and are not intended to limit the scope of the invention in any manner. For a legal definition of the proper scope of the invention, attention is directed to the several appended claims.

EXAMPLE 1

17,17-ethylenedioxy-3-methoxyestra-1,3,5(10),14-tetraene

Reflux, a mixture of 400 mg. of 14-dehydroestrone 3-methyl ether, 0.024 g. of p-toluenesulfonic acid monohydrate, 2.5 ml. of ethylene glycol, 0.24 ml. of ethyl orthoformate, and 60 ml. of benzene while stirring, with continuous separation of water for 7.5 hours. Wash the cooled mixture with an aqueous sodium bicarbonate solution. Dry the organic layer over anhydrous magnesium sulfate and evaporate in vacuo. The residue should weigh 330 mg., M.P. 105-113°. The analytical specimen from methyl alcohol exhibits M.P. 121-122°;

$\lambda_{\text{max}}^{\text{KBr}} 287 \mu\text{ (}\epsilon 2,070\text{)}, \lambda_{\text{max}}^{\text{KBr}} 3.47, 6.12, 6.23, 6.37, 6.66, 20$
 $7.00, 7.98, 8.70 \mu, [\alpha]_D^{25} = +80.64^\circ (\text{c.} = 1\% \text{ CHCl}_3)$

chromatographically homogeneous.

Analysis—Calcd. for $C_{21}H_{26}O_3$: C, 77.24; H, 8.03. Found: C, 77.42; H, 8.18.

EXAMPLE 2

3-hydroxyestra-1,3,5(10),14-tetraen-17-one

Heat 100 mg. of 14-dehydroestrone 3-methyl ether and 1.5 g. of freshly prepared pyridine hydrochloride together at 210° for 40 minutes under a nitrogen atmosphere. Cool the mixture, add 5 ml. of 5% hydrochloric acid, extract the mixture with ether, and wash the ether extracts well with water and with 5% potassium hydroxide solution. Acidify the alkaline extract to precipitate the product, 14-dehydroestrone, and recover by filtration.

EXAMPLE 3

17,17-ethylenedioxyestra-1,3,5(10),14-tetraen-3-ol

Reflux ten grams of 14-dehydroestrone, 1.5 g. of p-toluenesulfonic acid, 750 ml. of benzene, and 100 ml. of ethylene glycol with continuous removal of water via a Dean-Stark apparatus for twenty hours. Wash the benzene solution with saturated aqueous sodium bicarbonate solution, then with water, and finally evaporate under vacuum. Dissolve the residue in methanol, concentrate, and dilute with hexane. Precipitate the product, 14-dehydroestrone 17-ethylene ketal, and remove by filtration.

EXAMPLE 4

3-ethoxy-17,17-ethylenedioxyestra-1,3,5(10),14-tetraene

Dissolve one gram of 14-dehydroestrone 17-ethylene ketal in 35 ml. of ethanol containing 5 ml. of ethyl bromide and 350 mg. of sodium hydroxide. Reflux the mixture for 18 hours, and remove the solvents under vacuum. Take the residue up in carbon tetrachloride, and wash the carbon tetrachloride solution several times with 5% sodium hydroxide solution, and then with water until neutral. Evaporate the solution under vacuum, and crystallize the residue from methanol, to yield the pure product 3-ethoxy-17,17-ethylenedioxyestra-1,3,5(10),14-tetraene.

EXAMPLE 5

3-allyloxy-17,17-ethylenedioxyestra-1,3,5(10),14-tetraene

Dissolve one gram of 14-dehydroestrone 17-ethylene ketal in 50 ml. of ethanol, and add 5 ml. of allyl bromide, together with 280 mg. of sodium hydroxide. Reflux the mixture for 20 hours, and remove the solvents under vacuum. Dissolve the residue so obtained in carbon tetrachloride, and wash the solution with 5% sodium hydroxide solution, and then with water. Reduce the thoroughly dried carbon tetrachloride solution in volume under vacuum until solids precipitate. Recrystallize the solids thus obtained from alcohol, thus affording the pure product, 3-

allyloxy - 17,17 - ethylenedioxyestra - 1,3,5(10),14 - tetraene.

EXAMPLE 6

3-cyclopentyloxy-17,17-ethylenedioxyestra-1,3,5(10),14-tetraene

Dissolve five hundred milligrams of 14-dehydroestrone 17-ethylene ketal in 25 ml. of ethanol, and add 5 ml. of cyclopentyl bromide along with 500 mg. of sodium hydroxide. Reflux the mixture overnight, and then remove the solvents in vacuo. Dissolve the dried residue in carbon tetrachloride and extract the solution thus obtained several times with 5% aqueous sodium hydroxide solution. Wash the washed organic solvent solution with distilled water until neutral, and then remove the solvent in vacuo. Dissolve the solids therefrom in ethanol and concentrate, so as to cause deposition of the pure crystals of 3-cyclopentyloxy-17,17-ethylenedioxyestra - 1,3,5(10),14-tetraene.

EXAMPLE 7

3-benzyloxy-17,17-ethylenedioxyestra-1,3,5(10),14-tetraene

Reflux a mixture of 500 mg. of 14-dehydroestrone 17-ethylene ketal, 25 ml. of ethanol, 3 ml. of benzyl bromide, and 175 mg. of sodium hydroxide for 20 hours under nitrogen. Remove the organic solvents under vacuum, and dissolve the residue in carbon tetrachloride. Wash the carbon tetrachloride solution with 5% sodium hydroxide solution and with water, and then evaporate under vacuum. Recrystallize the solids thus obtained from methanol several times to obtain the pure product 3-benzyloxy-17,17-ethylenedioxyestra-1,3,5(10),14-tetraene.

EXAMPLE 8

3-methoxy-17,17-trimethylenedioxyestra-1,3,5(10),14-tetraene

Treat a solution of 1.0 g. of 14-dehydroestrone 3-methyl ether in 150 ml. of dry benzene with 10 ml. of 1,3-propanediol and 100 mg. of p-toluenesulfonic acid. Reflux the mixture for 20 hours, with continuous removal of water via a Dean-Stark apparatus, cool, and wash with saturated sodium bicarbonate solution and with water. Dry the benzene solution over anhydrous magnesium sulfate and concentrate in vacuo. Dissolve the solids therefrom obtained in ethyl acetate, concentrate slightly, and precipitate by the addition of petroleum ether. Recover the pure product 3-methoxy-17,17-trimethylenedioxyestra-1,3,5(10),14-tetraene by filtration.

EXAMPLE 9

17,17-ethylenethioxy-3-methoxyestra-1,3,5(10),14-tetraene

Reflux a solution of 1.0 g. of 14-dehydroestrone 3-methyl ether and 100 mg. of p-toluenesulfonic acid in 150 ml. of dry benzene containing 1 ml. of 2-mercaptoethanol for 4 hours with continuous separation of water from the reaction. Cool the solution, wash with aqueous sodium bicarbonate solution and with water and dry over anhydrous magnesium sulfate. Evaporate the dried solution under vacuum to afford a crystalline residue, then crystallize several times from methanol to yield the pure 17,17-ethylenethioxy-3-methoxyestra-1,3,5(10),14-tetraene.

EXAMPLE 10

17,17-ethylenedithio-3-methoxyestra-1,3,5(10),14-tetraene

Cool a mixture of 5.0 g. of 14-dehydroestrone 3-methyl ether, 5 ml. of ethanedithiol and 20 ml. of chloroform to 5°. Bubble hydrogen chloride through the solution for 3 hours, and then remove the solvents under vacuum. Dissolve the solid residue so recovered in hot acetone, concentrate somewhat, and dilute with hexane to precipi-

tate the pure 17,17-ethylenedithio-3-methoxyestra-1,3,5-(10),14-tetraene.

EXAMPLE 11

3-acetoxy-17,17-ethylenedioxyestra-1,3,5(10),14-tetraene

Dissolve one gram of 14-dehydroestrone 17-ethylene ketal in 10 ml. of dry pyridine to which 3 ml. of acetic anhydride has been added. Keep the solution at room temperature for 18 hours, and then remove the solvents under vacuum. Crystallize the solid material thus obtained from acetone and petroleum ether to yield the pure 3-acetoxy-17,17-ethylenedioxyestra-1,3,5(10),14-tetraene.

EXAMPLE 12

3-benzoyloxy-17,17-ethylenedioxyestra-1,3,5(10),14-tetraene

Treat a solution of 500 mg. of 14-dehydroestrone 17-ethylene ketal in 8 ml. of dry pyridine with 2 ml. of benzoyl chloride. Let the solution stand for 24 hours, and then remove the solvents under vacuum. Dissolve the solids thus recovered in warm acetone, concentrate the solution somewhat, and add hexane slowly until crystallization commences. Recover the pure 3-benzoyloxy-17,17-ethylenedioxyestra-1,3,5(10),14-tetraene by filtration.

EXAMPLE 13

17,17-ethylenedioxyestra-1,3,5(10),7-tetraen-3-ol

Stir and distill a mixture of 900 mg. of equilin, 100 mg. of p-toluenesulfonic acid monohydrate, and 160 ml. of ethylene glycol over a period of 1 hour at 6 mm. pressure with a still head temperature of 83°. After this period, add an additional 100 ml. of ethylene glycol and continue the distillation at 6 mm. pressure for one more hour. A volume of 230 ml. of distillate is to be collected over the two hour period. Cool the reaction mixture and adjust to a pH of 8.5 with an aqueous sodium bicarbonate solution. Extract the product with ether. Dry the organic layer over anhydrous magnesium sulfate and evaporate in vacuo. Repeat crystallizations from acetonitrile so that the crude residue may yield 188 mg. of material, M.P. 155-156°,

$\lambda_{\text{max}}^{\text{EB}} 2.95, 3.42, 6.16, 6.33, 6.66\mu, \lambda_{\text{max}}^{\text{E:OH}} 280 \text{ m}\mu (\epsilon = 1,920)$, $[\alpha]_D^{25} = +158.0^\circ (\text{c.} = 1\% \text{ CHCl}_3)$

Analysis.—Calcd. for $\text{C}_{20}\text{H}_{24}\text{O}_3$: C, 76.89; H, 7.74. Found: C, 76.72; H, 7.42.

EXAMPLE 14

17,17-ethylenedioxy-3-methoxyestra-1,3,5(10),7-tetraene

Cool a solution of 1.0 g. of equilin 17-ethylene ketal and 12.0 g. of potassium hydroxide in 35 ml. of water and 100 ml. of methyl alcohol to 22°. To this cooled solution, add 11.0 ml. of dimethyl sulfate with agitation over a period of 35 minutes, while maintaining the temperature between 22 and 28°. Allow the reaction mixture to agitate at 25° for an additional 1.25 hours. Dilute the mixture to 500 ml. with water and cool to 10°. Collect the product by filtration, wash with water and dry. Recrystallize the crude product from methanol to yield 181 mg. of 17,17-ethylenedioxy-3-methoxyestra-1,3,5(10),7-tetraene, M.P. 148-150°,

$\lambda_{\text{max}}^{\text{EB}} 3.43, 3.52, 6.22, 6.33, 6.65\mu, \lambda_{\text{max}}^{\text{E:OH}} 280 \text{ m}\mu (\epsilon = 1,710)$, $[\alpha]_D^{25} = +144.9^\circ (\text{c.} = 1\% \text{ CHCl}_3)$

chromatographically homogeneous.

Analysis.—Calcd. for $\text{C}_{21}\text{H}_{26}\text{O}_3$: C, 77.27; H, 8.03. Found: C, 76.91; H, 7.90.

EXAMPLE 15

3-ethoxy-17,17-ethylenedioxyestra-1,3,5(10),7-tetraene

Reflux two grams of equilin 17-ethylene ketal with 50 ml. of ethanol containing 10 ml. of ethyl bromide and 700 mg. of sodium hydroxide. Continue reflux for 20

hours, evaporate the organic solvent solution and dissolve the solid residue in carbon tetrachloride. Wash the organic solvent solution of product with 5% sodium hydroxide solution and then with water, and finally dry over anhydrous magnesium sulfate. Evaporate the dried solution under vacuum, and recrystallize the crystalline material from methanol to yield the pure product 3-ethoxy-17,17-ethylenedioxyestra-1,3,5(10),7-tetraene.

EXAMPLE 16

3-allyloxy-17,17-ethylenedioxyestra-1,3,5(10),7-tetraene

Reflux one gram of equilin 17-ethylene ketal, 30 ml. of ethanol, 5 ml. of allyl bromide, and 300 mg. of sodium hydroxide together for 20 hours. Remove the solvents under vacuum, and dissolve the solid residue in carbon tetrachloride; wash solution with 5% sodium hydroxide solution and with water until neutral. Evaporate the solvent and recrystallize the solid product from alcohol to yield the pure 3-allyloxy-17,17-ethylenedioxyestra-1,3,5(10),7-tetraene.

EXAMPLE 17

3-cyclopentyloxy-17,17-ethylenedioxyestra-1,3,5(10),7-tetraene

Reflux overnight a mixture of 1 g. of equilin 17-ethylene ketal, 30 ml. of ethanol, 10 ml. of cyclopentyl bromide and 750 mg. of sodium hydroxide, and then remove the solvents under vacuum. Dissolve the dried residue in carbon tetrachloride and wash the solvent solution with 5% sodium hydroxide solution and then with water. Dry the washed solution over anhydrous magnesium sulfate and evaporate under vacuum. Recrystallize the solids thus obtained from methanol to yield the pure product, 3-cyclopentyloxy-17,17-ethylenedioxyestra-1,3,5(10),7-tetraene.

EXAMPLE 18

3-benzylxy-17,17-ethylenedioxyestra-1,3,5(10),7-tetraene

Reflux for 24 hours a solution containing 1.0 g. of equilin 17-ethylene ketal, 5 ml. of benzyl bromide, 350 mg. of sodium hydroxide in 50 ml. of ethanol. Remove the organic solvents under vacuum, and dissolve the dried residue in carbon tetrachloride. Wash the carbon tetrachloride solution with 5% sodium hydroxide solution and then with water. Remove the solvent under vacuum, and recrystallize the crystalline solids thereupon obtained several times from methanol to afford the pure product, 3-benzylxy-17,17-ethylenedioxyestra-1,3,5(10),7-tetraene.

EXAMPLE 19

3-methoxy-17,17-trimethylenedioxyestra-1,3,5(10),7-tetraene

Treat one gram of equilin 3-methyl ether dissolved in 135 ml. of dry benzene with 60 mg. of p-toluenesulfonic acid and 10 ml. of 1,3-propanediol. Reflux the mixture for 18 hours with continuous removal of water via a Dean-Stark apparatus. Cool the mixture, wash with saturated sodium bicarbonate solution and then with water, dry over anhydrous magnesium sulfate, and evaporate under vacuum. Dissolve the solids in ethyl acetate, concentrate slightly, and dilute the solution with hexane to cause precipitation of the product, 3-methoxy-17,17-trimethylenedioxyestra-1,3,5(10),7-tetraene and recover by filtration.

EXAMPLE 20

17,17-ethylenethioxy-3-methoxyestra-1,3,5(10),7-tetraene

Reflux for 6 hours a solution of 1 g. of equilin 3-methyl ether and 60 mg. of p-toluenesulfonic acid in 150 ml. of benzene containing 2 ml. of 2-mercaptoethanol, with continuous removal of water with a Dean-Stark apparatus. Cool the solution, wash with saturated sodium bicarbonate

solution and then with water. Evaporate the dried solvent solution under vacuum, and recrystallize the recovered crystalline product from methanol, thus to afford the pure 17,17-ethylenethioxy-3-methoxyestra-1,3,5(10),7-tetraene.

EXAMPLE 21

17,17-ethylenedithio-3-methoxyestra-1,3,5(10),7-tetraene

Cool a mixture of 10 g. of equilin 3-methyl ether, 50 ml. of ethanedithiol, and 50 ml. of chloroform to 5°, then bubble hydrogen chloride through the solution for 3 hours. Remove the solvents under vacuum, and dissolve the solids thus obtained in hot acetone, concentrate slightly, and cool to deposit the pure product, 17,17-ethylenedithio-3-methoxyestra-1,3,5(10),7-tetraene.

EXAMPLE 22

3-acetoxy-17,17-ethylenedioxyster-1,3,5(10),7-tetraene

Dissolve 1 g. of equilin 17-ethylene ketal in 15 ml. of dry pyridine, and add 5 ml. of acetic anhydride. Allow the solution to stand at room temperature for 20 hours, at which time remove the solvents under vacuum to obtain the product equilin 17-ethylene ketal 3-acetate. Recrystallize from acetone and petroleum ether to effect further purification.

EXAMPLE 23

3-benzoyloxy-17,17-ethylenedioxyster-1,3,5(10),7-tetraene

Dissolve 100 mg. of equilin 17-ethylene ketal in 5 ml. of dry pyridine and add 2 ml. of benzoyl chloride. Remove the solvents under vacuum after letting stand for 18 hours. Dissolve the gummy residue in warm acetone and concentrate slightly, then add petroleum ether to the concentrated solution. Remove by filtration the product equilin 17-ethylene ketal 3-benzoate after crystallization occurs.

EXAMPLE 24

3-methoxy-17,17-ethylenedioxyster-1,3,5(10),6-tetraene

Cool to 28° a solution of 1.14 g. of 6-dehydroestrone 17-ethylene ketal and 11.8 g. of potassium hydroxide in 30 ml. of water and 60 ml. of methyl alcohol. To this cooled solution add 11.0 ml. of dimethyl sulfate with agitation over a period of 35 minutes while the temperature is maintained between 28 and 30°. Continue the agitation for 1.5 hours at room temperature. Dilute the mixture with water and cool to 10°. Collect the resulting precipitate by filtration, wash with water and dry. The product will weigh 330 mg., M.P. 74-80°. Obtain the analytical sample by repeated crystallization from methyl alcohol, M.P. 75-76°.

$\lambda_{\text{max}}^{\text{KBr}} = 3.45, 6.13, 6.24, 6.37, 6.68 \mu$; $\lambda_{\text{max}}^{\text{EtOH}} = 2.21 \text{ m}\mu$ ($\epsilon = 26,000$), $261 \text{ m}\mu$ ($\epsilon = 6,780$), $301 \text{ m}\mu$ ($\epsilon = 2,320$); $[\alpha]_{\text{D}}^{25} = 227.2^\circ$ ($c = 1\% \text{ CHCl}_3$).

Analysis.—Calcd. for $\text{C}_{21}\text{H}_{26}\text{O}_3$: C, 77.27; H, 8.03. Found: C, 77.53; H, 7.92.

EXAMPLE 25

3-ethoxy-17,17-ethylenedioxyster-1,3,5(10),6-tetraene

Treat one gram of 6-dehydroestrone 17-ethylene ketal with 35 ml. of ethanol containing 5 ml. of ethyl bromide and 350 mg. of sodium hydroxide. Reflux for twenty hours. The solvents will then be evaporated. Dissolve the residue in carbon tetrachloride. Wash the carbon tetrachloride solution with a 5% solution of sodium hydroxide, then with water. Dry the organic layer over anhydrous magnesium sulfate. Evaporate under vacuum, obtaining the product as white crystals which can be recrystallized from methanol, yielding pure 3-ethoxy-17,17-ethylenedioxyster-1,3,5(10),6-tetraene.

EXAMPLE 26

3-allyloxy-17,17-ethylenedioxyster-1,3,5(10),6-tetraene

5 Reflux a mixture of 500 mg. of 6-dehydroestrone 17-ethylene ketal, 15 ml. of ethanol, 2 ml. of allyl bromide, and 140 mg. of sodium hydroxide overnight. Remove the solvents under vacuum; dissolve the residue in carbon tetrachloride and wash the solvent solution with 5% sodium hydroxide solution and then with water until neutral. Evaporate the solvent and the product recovered will be a white solid. Recrystallize from methanol to afford the sought product 3-allyloxy-17,17-ethylenedioxyster-1,3,5(10),6-tetraene.

15

EXAMPLE 27

3-cyclohexyloxy-17,17-ethylenedioxyster-1,3,5(10),6-tetraene

20 Reflux for twenty-four hours a mixture of 2 g. of 6-dehydroestrone 17-ethylene ketal with 60 ml. of ethanol, 20 ml. of cyclohexyl bromide and 1.5 g. of sodium hydroxide. Following this remove the solvents under vacuum. Dissolve the residue containing the product 3-cyclohexyl ether and some unreacted 3-phenol in carbon tetrachloride and wash with 5% sodium hydroxide solution and then with water. Concentrate the dried organic solution under vacuum and the crystalline product 3-cyclohexyloxy-17,17-ethylenedioxyster-1,3,5(10),6-tetraene will be recovered.

30

EXAMPLE 28

3-benzylloxy-17,17-ethylenedioxyster-1,3,5(10),6-tetraene

35 Reflux under nitrogen for twenty hours one gram of 6-dehydroestrone 17-ethylene ketal, 50 ml. of ethanol, 5 ml. of benzyl bromide, and 350 mg. of sodium hydroxide. Remove the organic solvents under vacuum, and dissolve the residue in carbon tetrachloride. Wash the carbon tetrachloride solution with 5% sodium hydroxide solution and then with water. After this, dry and evaporate the solution. Dissolve the residue in hot methanol and cool to precipitate the desired 3-benzylloxy-17,17-ethylenedioxyster-1,3,5(10),6-tetraene.

45

EXAMPLE 29

3-methoxy-17,17-trimethylenedioxyster-1,3,5(10),6-tetraene

50 Treat a solution of 1.0 g. of 6-dehydroestrone 3-methyl ether in 150 ml. of benzene with 60 mg. of p-toluenesulfonic acid and 10 ml. of 1,3-propanediol. Reflux the mixture for 20 hours with continuous removal of water of reaction via a Dean-Stark tube. Wash the cooled mixture with cold saturated aqueous sodium bicarbonate solution and with water. Evaporate the organic layer and recrystallize the solid residue from ethyl acetate and hexane to yield the pure product 3-methoxy-17,17-trimethylenedioxyster-1,3,5(10),6-tetraene.

60

EXAMPLE 30

17,17-ethylenethioxy-3-methoxyestra-1,3,5(10),6-tetraene

65 Reflux for four hours a solution of 5.0 g. of 6-dehydroestrone 3-methyl ether and 300 mg. of p-toluenesulfonic acid in 800 ml. of benzene containing 5 ml. of 2-mercaptoethanol. Continuous separation of water is accomplished by means of a Dean-Stark tube. Wash the cooled solution with aqueous sodium bicarbonate solution, and evaporate the dried organic layer to dryness under vacuum. Recrystallize the crystalline residue from methanol to obtain the pure 17,17-ethylenethioxy-3-methoxyestra-1,3,5(10),6-tetraene.

75

EXAMPLE 31
17,17-ethylenedithio-3-methoxyestra-1,3,5(10),6-tetraene

Cool to 5° a mixture of 5 g. of 6-dehydroestrone 3-methyl ether, 5 ml. of ethanedithiol and 20 ml. of chloroform. Bubble hydrogen chloride through the solution for three hours, then remove the solvents under vacuum. Triturate the solid residue with a small volume of petroleum ether. Filter and recrystallize the crystalline product several times from acetone to obtain the pure 17,17-ethylenedithio-3-methoxyestra-1,3,5(10),6-tetraene.

We claim:

1. A compound of the general structure:

wherein R represents a substituent selected from the group consisting of hydrogen, lower alkyl, lower alkenyl, cycloalkyl, of up to 6 carbon atoms, benzyl, lower alkanoyl and benzoyl; and W represents a member selected from the group consisting of lower alkylenedioxyethylene of up to 6 carbon atoms, lower alkylenedithiomethylene, of up to 6 carbon atoms and lower alkylenthioxymethylene of up to 6 carbon atoms.

2. A compound according to claim 1 where R represents

a lower alkyl group and W represents lower alkylenedioxyethylene of up to 6 carbon atoms.

3. 17,17-ethylenedioxy-3-methoxyestra-1,3,5(10),14-tetraene.
4. 17,17-ethylenedioxyestra-1,3,5(10),14-tetraen-3-ol.
5. A process for preparing a partially dehydrogenated 17-ketal of an estrogenic steroid which comprises acylating an estrone alkyl ether at the reflux temperature of the acylating agent to form the 17-enol acylate thereof, halogenating to form the 16-halogeno substituted analog thereof, ketalizing by treating with a lower alkylene glycol at the reflux temperature of the inert solvent employed to form the 16-halogenated 17-ketal analog, dehydrohalogenating by treating with an alkali metal tertiary alkoxide to remove the halogen substituent and form a Δ¹⁵ bond, treating this compound with paratoluenesulfonic acid to cause the Δ¹⁵ bond to shift to a Δ¹⁴-position and remove the ketal group and ketalizing by treating with a lower alkylene glycol this compound to replace the 17-ketal substituent to obtain the product of the invention.

UNITED STATES PATENT OFFICE
CERTIFICATE OF CORRECTION

Patent No. 3,189,605

June 15, 1965

Herchel Smith et al.

It is hereby certified that error appears in the above numbered patent requiring correction and that the said Letters Patent should read as corrected below.

Column 5, line 20, for "287" read -- 277 --; column 6, line 31, for "vacum" read -- vacuum --; column 8, line 63, or "dliute" read -- dilute --; column 9, line 19, for "equalin" read -- equilin --; column 10, line 37, for "deyhydroestrone" read -- dehydroestrone --; column 12, line 10, or "16-hologeno" read -- 16-halogeno --.

Signed and sealed this 3rd day of May 1966.
